UNITED STATES PATENT OFFICE.

HERMAN H. OLSEN, OF WHITEHALL, MICHIGAN.

INTEREST-COMPUTING AND MULTIPLYING MACHINE.

1,203,392.

Specification of Letters Patent.

Patented Oct. 31, 1916.

Application filed December 7, 1914. Serial No. 875,872.

To all whom it may concern:

Be it known that I, HERMAN H. OLSEN, a citizen of the United States of America, residing at Whitehall, in the county of 5 Muskegon and State of Michigan, have invented certain new and useful Improvements in Interest-Computing and Multiplying Machines; and I do hereby declare the following to be a full, clear, and exact description of the invention, such as will enable others skilled in the art to which it 10 appertains to make and use the same.

This invention relates to an interest computing and multiplying device by means of 15 which the interest on any desired sum may be computed at any given rate or per cent., for any particular length of time, the device also being adapted to be used in finding products resulting from the multiplication 20 of any selected multiplicand by any multiplier.

It is the object and purpose of this invention to construct a device of this character by means of which these several computations 25 may be quickly and easily made and the result accurately determined, said construction being of very simple and economical design and very readily and easily operated.

30 To these ends I have constructed the device shown in the accompanying drawing, in which:—

Figure 1 is a plan view of the device; Fig. 2 is a vertical section taken transversely 35 of said device; and Fig. 3 is a view of a portion of a computing sheet secured to one of the rolls used in the construction of the device.

Like reference characters refer to like 40 parts throughout the several views of the drawing.

In the embodiment disclosed there is provided a casing having parallel sides *a* connected by parallel ends *b*, there being secured to said sides and ends any suitable base while at the upper edges of the sides and ends a plate *c*, preferably of glass, though it may be of any other suitable transparent material, is slidably mounted, 45 being retained by clips *d* against accidental displacement. On the underside of the plate a sheet of opaque material is fastened, said sheet having a plurality of rows of openings *e* which are separated from each other by 50 cut-off partitions *g* as shown, these rows being located lengthwise of the plate and with 55 openings in one row directly below those in the row next above.

The rows of openings are shown as four in number and immediately below said openings are mounted four rolls *h* having journals extending into and rotatably mounted in the ends *b* of the casing, there being provided turn buttons *i* by means of which the rolls may be manually operated. In the 60 drawing said buttons are indicated at one end of the device but it is apparent they may be placed at either end or at both ends if desired. Each roll *h* has secured on the outer surface thereof a sheet *k* which has 65 printed thereon a plurality of numbers at one end indicating a principal on which an interest is to be computed and thence in horizontal lines indicating the computed interest at the rate of 6% per annum for a plurality of numbers of days. In the present 70 construction said days are indicated in horizontal alinement in column C ranging from ten days to five hundred and forty days, as will be apparent from reference to Fig. 1. 75 The uppermost roll may be known as the thousands roll including all principals from one thousand to nine thousand, the second roll in similar manner is the hundreds roll, the third, the tens roll and the fourth, the 80 units roll. It is of course apparent that additional rolls may be used, for instance, tens of thousands or hundreds of thousands if needed. The plate *c* is slidably mounted 85 in the casing and has secured thereto a tab *m* by means of which it may be drawn 90 manually to different positions. Secured also to the underside of the plate *c* at the lower edge thereof, as shown in Fig. 1, is an opaque strip on which is printed a column 95 of per cents. beginning at 1% and ending at 54%, this column being indicated at B. The principal on which the interest is to be 100 computed will be read downward, that shown in Fig. 1 being 2854 and the principal column is denoted by reference character A. It will be noted also that on the basis of a 6% computation the vertical column under each multiple of 60 will be the same multiple of the principal indicated at the left 105 hand side of the device as shown in Fig. 1 in the principal column A. For instance, in the vertical column under the number 180, disregarding the decimal point, will be 110 found the figures, 6,000, 2400, 150 and 12, this being three times the numbers disclosed at the left in column A which are respec-

tively 2,000, 800, 50 and 4. In the same manner under the number 540 the multiple is 9 and under the number 420 the multiple is 7; and if desired fractional multiples may be used as for instance, under the number 80 the multiple will be $1\frac{1}{3}$ and so on.

Let it be supposed that the interest on \$2,854.00 at 6% per annum for 65 days is to be found. The operation in such case is to turn the several rolls so that the principal reading downward from the upper roll will appear as 2,000, 800, 50 and 4 on the four rolls. Under the numeral 60 of the days column C we find respectively 20.00, 8.00, .50 and .04, the sum of which is the required interest on the said sum at 6% for 60 days, or \$28.54. For the additional 5 days attention should then be directed to the figures appearing under the number 50 in column C, the slide *c* being moved over to the left far enough that the cut-off partition *g* will cut off the last figure appearing on each of the rolls under the numeral 50. In this case such numbers are 1.67, .67, .04 and .00, the sum of which added to \$28.54 is \$30.92 or the required interest. It will be clear that by operating the slide *c* the interest for any required number of days less than 10 may be obtained by merely cutting off the last figure of the numbers appearing under a number in column C which is ten times the number of days desired.

The foregoing is the operation where the interest is at the rate of 6% per annum. Suppose however, it is desired to find the interest at a different rate for instance, at 4½% per annum. In this case it is necessary to interpolate a new principal which at 6% per annum will have the same interest computation as the given principal at 4½%. This interpolation is made in the following manner: Let the principal be \$2,854, the rate 4½% and the time 100 days. The first operation then is to pass to the per cent. column B to the position occupied by 4½% and it will be noted that above such position, disregarding the decimal point, reading downward, are the figures 1500, 600, 37 and 3, the sum of which is 2,140. These figures, it will be noted, bear the same ratio to those over the six per cent. character as does 4½ to 6, and the interest on the sum thereof at six per cent. accordingly, is the same as the interest on 2,854 at four and one-half per cent. for any given time. Or as will later appear, the multiplier by which 2854 is multiplied to obtain the new principal is 4½ divided by 6. This is the new principal which should be used in place of \$2,854, the rolls being operated so that 2,000 shall appear on the thousands roll, one hundred on the hundreds roll, 40 on the tens roll, with no figures showing on the units roll. Then by passing over to the figures appearing under 100 days will be found the interest

on the sums 2,000, 100 and 40 which added together will give the interest for 100 days at 4½% on \$2,854. The same operation may be gone through with to determine the interest at any other desired rate for any other number of days. I have used a certain principal, namely \$2,854, merely as a matter of example but any principal from \$1.00 to \$9,999.00 may be used.

It is of course apparent that the interpolated principal may at some times be more than 9,999. For example suppose that it should be 23,421. With four rolls only as in the device shown, it would be necessary to use the first four figures of this sum or 2,342 as the principal obtaining the interest on this sum at the desired rate for the required number of days and multiplying it by 10 and afterward adding the interest on the \$1.00 additional at the given rate for the required number of days. Of course as heretofore noted the mechanism is not limited to the four rolls but may have additional rolls if desired, to take care of such contingencies.

The following illustration will show how the device may be used in the process of multiplying. The multiplicand is 2,854 which is to be multiplied by 623. For this multiplication the first operation is to pass to the numeral 180 which is three times 60 in column C and add up the figures appearing underneath, disregarding the decimal point, the sum of which will be 8,562 which may be marked down in any convenient manner. This multiplies the selected multiplicand by the units digit 3. To multiply by 2 the tens digit the figures under the 120 numeral which is two times 60 are added together amounting to 5,708 to which an 0 is added making 57,080 by reason of the fact that the multiplicand is being multiplied by 20 instead of 2 as in 623 the 2 occupies tens place; and finally to multiply by the 6 the figures under the 360 day numeral which is six times 60 are added together amounting to 17,124 to which two 00's are added as the 6 is in hundreds place making 1,712,400, then by adding together 8,562, 57,080 and 1,712,400 the product will be obtained being 1,778,042. In the same way multiplication by any of the fractional multipliers shown in the column indicated as "Multiplier" column may be had to determine the product of any selected multiplicand by said fractional multiplier.

Various changes in minor detail of construction may be resorted to without departing from my invention which is adapted to be used in the manners indicated and in other ways not specifically described. The claims define the invention and all modifications falling within their scope are to be considered as comprehended within the invention.

I claim:—

1. In a device of the character described, a casing, a closure mounted at the upper side thereof and having a plurality of rows 5 of transparent sections therein, a roll rotatably mounted below each row of transparent sections, each roll having thereon a plurality of rows of computations of interest on a plurality of principals for different times 10 at a given rate, said computations being adapted to show through the transparent sections of the closure, a column having represented therein the numbers of days for the said computations located at 15 one side of the casing and with said numbers in operative alinement with the computations corresponding thereto and a column at the opposite side of the casing secured to the slide containing a plurality of per cents., 20 each being one tenth of the respective number of days in the days column directly opposite at the opposite side of the casing.

2. In a device of the character described, a casing, a closure mounted at the upper side 25 thereof and having a plurality of rows of

transparent sections therein, a roll rotatably mounted below each row of transparent sections, each roll having thereon a plurality of rows of computations of interest on a plurality of principals for different times 30 at a given rate, said computations being adapted to show through the transparent sections of the closure, and a column having represented therein the numbers of days for the said computations located at one side of 35 the casing and with said numbers in operative alinement with the computations corresponding thereto, and a second column similarly located at the opposite side of the casing denoting a plurality of per cents., 40 each per cent. being one tenth of the corresponding numbers of days in the first column.

In testimony whereof I affix my signature in presence of two witnesses.

HERMAN H. OLSEN.
